PAPERHANGER'S BRUSH AND ROLLER

Stanley S. Kozub, Cleveland, Ohio

Application September 20, 1938, Serial No. 230,884

1 Claim. (Cl. 216—61)

This invention relates to a paperhanger's brush and seam roller, the general object of the invention being to provide means whereby a seam roller is removably attached to the brush so that the paperhanger will always have the roller ready for use and need not have to hunt through his pockets for the roller when he wishes to roll the seam of the paper.

This invention also consists in certain other features of construction and in the combination and arrangement of the several parts to be hereinafter fully described, illustrated in the accompanying drawing and specifically pointed out in the appended claim.

15 In describing the invention in detail, reference will be had to the accompanying drawing wherein like characters denote like or corresponding parts throughout the several views, and in which:

Figure 1 is a side view of the brush showing two sockets therein with the shaft of a roller supported in one socket.

Figure 2 is a front view of the roller.

Figure 3 is a top plan view of the roller.

Figure 4 is a fragmentary sectional view showing how the shaft from the roller fits in the socket.

In this drawing the numeral 1 indicates the handle part of the brush used by a paperhanger and the numeral 2 indicates the bristles thereof. 30 In carrying out my invention I form a socket 3 in the curved corner part 4 at each end of the handle part 1 and a bushing 5 is pressed into said socket and is held therein by the screws 6 passing through a flange 7 formed on the outer end 35 of the bushing and said screws extending into the handle part 1. The bushing is provided intermediate its end with a groove 7 which is of substantially semi-circular shape in cross section. The roller is shown at 8 and is carried by a yoke 40 9 and a shank 10 is connected with the yoke and is adapted to enter either one of the bushings 5. Both the bushings and the shank 10 are of rectangular shape in cross section to prevent turning movement of the shank 10 in the bushing. The shank 10 is removably held in the bushing by a ball 11 engaging a part of the groove 7 and pressed into the groove by a spring 12 engaging the ball and held in place by a threaded plug 13 threaded into the bore 14 which ex-

tends transversely across the shank 10 and receives the ball and the spring. By adjusting the plug 13 the tension of the spring can be adjusted to regulate the force with which the ball will engage the groove.

Thus a seam roller is attached to the handle of the brush so that after the brush has been used to put a strip of paper on a wall by slightly turning the wrist the paperhanger can bring the roller against the seam between the two strips of paper to roll the same and as the roller is attached to the brush there is no danger of the roller becoming lost or the paperhanger losing time in trying to find the roller in his pockets. The shank 10 can be placed in either one of the 15 sockets 3 or if desired two types of rollers can be attached to the brush, such as the cylindrical seam roller or a lap roller.

It is thought from the foregoing description that the advantages and novel features of the invention will be readily apparent.

It is to be understood that changes may be made in the construction and in the combination and arrangement of the several parts provided that such changes fall within the scope of the 25 appended claim.

Having described the invention, what is claimed as new is:

In a device of the class described, an elongated flat handle having a recess in one of the corners 30 at one side of the handle, the wall of said recess being of arcuate shape and said handle having a socket therein of square shape in cross section, which opens out through the central portion of said arcuate wall, said socket extending at an 35 incline to the axis of the handle and sloping toward the adjacent end of the handle, a bushing fitting in said socket and also of square shape in cross section and said bushing having an endless groove therein extending across intermediate 40 portions of its four walls, a shank having a yoke at one end, a seam roller rotatably carried by the yoke, said shank being of square shape in cross section to fit in the bushing and a detent carried by the shank for engaging a portion of the 45 groove to detachably hold the shank in the bushing in the socket with the roller partly fitting in the arcuate recess.

STANLEY S. KOZUB.
